COUNTERBALANCED PICKUP ARM

Lincoln Thompson, Cheshire, and Robert L. Stone,
Orange, Conn., assignors to The Soundscriber
Corporation, New Haven, Conn., a corporation
of Connecticut

Application July 26, 1943, Serial No. 496,110

6 Claims. (Cl. 274—23)

This invention relates to improvements in phonograph reproducing machines, and more particularly to a novel form of laterally counterbalanced reproducing arm which will permit the pickup needle to remain in its track and continue reproducing the record even when the machine is considerably off-level.

The present invention is especially designed for use with a phonograph reproducing from disk records having closely-spaced relatively shallow indented or embossed grooves of the type disclosed in Reissue Patent No. 22,183, issued September 22, 1942, to Lincoln Thompson, and entitled Apparatus for recording sound on thin discs.

This application is a continuation in part of our prior co-pending application, Serial No. 492-246, filed June 25, 1943, entitled Spring hinge mountings for sound recording and reproducing heads.

One object of the present invention is to provide a machine of the above nature, in which the reproducing arm is equipped with a counter-weight which is adapted to neutralize any lateral pickup-dislocating forces produced by tilting of the equipment to an off-level position. The use of the present invention is of particular importance when the recording machine is used on mobile vehicles such as trucks or tanks, on ship-board, or on airplanes which frequently assume off-level positions.

A further object is to provide a dictating machine of the above nature, in which the dislocating forces tending to move the pickup needle out of the record grooves being reproduced will be completely compensated for so that the reproduction will not be interfered with even though the vehicle undergoes frequent changes in speed, direction and inclination.

A further object is to provide a counter-balanced reproducing arm of the above nature, in which the counter-balancing weight will be readily adjustable with respect to the length of said arm.

A still further object of the present invention is to provide a reproducing arm of the above nature which will be relatively inexpensive to manufacture, simple in construction, compact, ornamental in appearance, and very efficient and durable in use.

With these and other objects in view there has been illustrated on the accompanying drawings one form in which the invention may be conveniently embodied in practice.

In the drawings,

Fig. 1 represents a top plan view of an improved disk record reproducing phonograph showing in full lines a counter-balanced reproducing arm.

Fig. 2 is a side view of the reproducing arm as it appears in use.

Fig. 3 is a plan view of the same.

Fig. 4 is a sectional view taken along the line 4—4 of Fig. 3, showing the construction of the pivotal mounting of the reproducing arm.

Fig. 5 is a rear view of the bearing bracket for the reproducing arm, showing the appearance of the improved wire "tracking" spring which assists in holding the reproducing needle in its track.

Referring now to the drawings wherein like reference numerals denote corresponding parts throughout the several views, the numeral 10 indicates a rectangular cabinet, over which a turntable 11 is adapted to be driven at constant speed by a suitable electric motor (not shown). The turntable 11 is provided with a vertical spindle 12 having a square top 12a which serves to centralize a thin record tablet 13 mounted upon the turntable 11, and also to prevent slipping of said record on said turntable.

A reproducing arm 17, comprising the present invention, is mounted to swing in a horizontal plane (when the machine is level) upon a vertical shaft 18, which is mounted on antifriction bearings in a U-shaped bearing bracket 19. The bracket 19 has a horizontal base 19a adapted to be secured in a fixed position upon the cabinet 10 by means of a pair of screws 19b, 19b. The shaft 18 is adapted to be connected rigidly to the reproducing arm 17 by means of a horizontal pin 18a, as clearly shown in Fig. 4.

In order to neutralize the lateral component of the force of gravity acting upon the pickup 40 parallel to the record surface due to the weight of the reproducing arm 17 and the head 30 whenever the dictating machine is located in an off-level position, provision is made of a rearwardly extending upwardly-offset auxiliary arm 20 connected to the rear portion of said reproducing arm 17 by screws 20a, 20a, and carrying upon its rear end a cylindrical counter-weight 21, the axis of which is horizontal and substantially in alignment with the longitudinal axis of the reproducing arm 17. The auxiliary arm 20 is preferably made of stiff flat metal stock, and the rear end 21aa of said arm 20 is adapted to be inserted within a thin horizontal slot 21a which passes entirely through the upper portion of the counter-weight 21, said arm 20 being locked in

any desired position in said counter-weight 21 by means of a set screw 21b.

Provision is also made of a light wire vertical "tracking" spring 22 which is adapted to be rigidly secured at its lower end to a rectangular plate 22a, attached, as by a lock screw 22b, to the lower portion of the rear surface of the U-shaped bearing bracket 19. The upper portion of the wire 22 extends loosely through a small aperture 22c formed in the upper offset portion 20aa of the auxiliary arm 20, as clearly shown in Figs. 1, 2, 4, and 5.

The vertical shaft 18 is journaled at its upper end in a conical screw bearing 23 having a slotted end 23a, said screw being locked in adjusted position by means of a nut 24 seated upon the top horizontal arm 19aa of the U-shaped bracket 19. The conical point 24aa of the screw bearing 23 is adapted to engage freely in a conical recess 18aa located in the top of the shaft 18.

The bottom of the shaft 18 is provided with a vertical hinge pin 25, preferably consisting of a hardened drill rod which has a driving fit within a vertical cylindrical recess formed in the lower end of the shaft 18 (as shown in Fig. 4).

The lower end of the hinge pin 25 is adapted to rest upon a small ball bearing 26 located in a socket 27 formed in an upstanding boss 28, located on the base 19a of the U-shaped bearing bracket 19. The ball bearing 26 is adapted to be held detachably in operating position by means of a threaded cup-shaped ball retainer 29 screwed into said socket 27, said retainer preferably being constructed of a long wearing material such as bronze.

The reproducing arm 17 is provided at its forward end with the pickup head 30, connected to said arm 17 as by a rectangular leaf spring hinge 31 (as clearly shown in Figs. 2 and 3).

In order to facilitate the lifting of the pickup head 30 from the record 13 whenever desired, provision is made of an upwardly inclined handle 33 detachably fastened to the forward end of said pickup head 30. The leaf spring hinge 31 is secured at its opposite ends to the reproducing arm 17 and pickup head 30 as by screws 34, 35, 36, 37, as shown.

For the purpose of counter-balancing the weight of the pickup head 30, provision is made, on the center portion of said pickup head 30, of an upstanding pin 38 which is connected by a helical coil 39 to an adjustable angle plate 40 having an elongated slot 41, within which are located a pair of adjusting screws 42 and 43, as clearly shown in Fig. 2 of the drawings.

While there has been disclosed in this specification one form in which the invention may be embodied, it is to be understood that this form is shown for the purpose of illustration only, and

that the invention is not to be limited to the specific disclosure but may be modified and embodied in various other forms without departing from the spirit. In short, the invention includes all the modifications and embodiments coming within the scope of the following claims.

Having thus fully described the invention what is claimed as new, and for which it is desired to secure Letters Patent, is:

10. 1. In a phonograph, a driven turntable, a disk record supported thereon, a reproducing arm mounted to swing parallel to said record, the rear end of said arm being mounted on a bearing shaft located at right angles to said record, said arm having a counter-balancing weight adjustably secured thereto at a point behind said bearing shaft to neutralize the component of the force of gravity acting upon the reproducing needle parallel to the record surface tending to swing the reproducing head needle out of its groove when the phonograph is tilted to an off-level position.
15. 2. In a phonograph machine, a reproducing arm mounted to swing in a plane parallel to said record, a bearing shaft perpendicular to said record for supporting the rear end of said arm, a rearwardly extending auxiliary arm secured to the rear portion of said reproducing arm and extending rearwardly beyond said bearing shaft thereof, and a cylindrical counter-weight adjustably secured upon the rear end of said auxiliary arm to neutralize lateral needle dislocating forces due to gravity acting parallel to the record surface when the machine is tilted off-level.
20. 3. The invention as set forth in claim 2 in which the counter-weight is located on substantially the same horizontal axis as said reproducing arm.
25. 4. The invention as defined in claim 2, in which said auxiliary arm is constructed of thin flat stiff material.
30. 5. The invention as set forth in claim 2, in which the rear portion of said auxiliary arm is secured to said counter-weight at a point above the center of said counter-weight.
35. 6. In a phonograph, a driven turntable, a disk record supported thereon, a reproducing arm mounted to swing parallel to said record, the rear end of said arm being mounted on a bearing shaft located at right angles to said record, said arm having a counter-balancing weight secured thereto at a point behind said bearing shaft to neutralize any components of the force of gravity acting parallel to the surface of said record tending to swing the reproducing head needle out of its groove when the phonograph is tilted to an off-level position.

LINCOLN THOMPSON.
ROBERT L. STONE.
